MAC MUNDY ANDREWS

SPUTUM CUP HOLDER

Filed Nov. 9, 1926

Patented Nov. 1, 1927.

1,647,427

UNITED STATES PATENT OFFICE.

MAC MUNDY ANDREWS, OF MORLEY, MICHIGAN; CHAUNCEY C. ANDREWS ADMINISTRATOR OF SAID MAC M. ANDREWS, DECEASED.

SPUTUM-CUP HOLDER.

Application filed November 9, 1926. Serial No. 147,360.

This invention relates to new and useful improvements in holders for sputum cups, and has for its primary object to provide a cup that is of such a construction as to maintain a collapsible sputum cup in such a manner as to prevent the same from being crushed, and at the same time permit of ready access to the cup when the same is desired for use.

10 A further and important object of the invention is to provide a holder for sputum cups wherein the open upper end of the cup is closed in an air tight manner when the lid of the holder is applied so that the germs 15 or bacteria may not escape.

A still further object is to provide a holder of this character that is extremely simple of construction, inexpensive of manufacture, and one that may be readily carried in the pocket and this without any liability of the material within the cup spilling therefrom.

Other objects will become apparent as the nature of the invention is better understood, 25 the same comprising the novel form, combination, and arrangement of parts herein-after more fully described, shown in the accompanying drawing and claimed.

In the drawing wherein like reference 30 characters indicate corresponding parts throughout the several views:

Figure 1 is a greatly enlarged detail section of a sputum cup holder constructed in accordance with the present invention.

35 Figure 2 is a reduced longitudinal section through the upper end thereof taken substantially upon the line 2-2 of Figure 1, and

Figure 3 is a fragmentary edge elevation 40 of the cup.

Now having particular reference to the drawings, 5 designates the body of the cup holder that may be of inexpensive metal or other suitable rigid material preferably of 45 rectangular configuration as disclosed more clearly in Figures 2 and 3. The upper open end of the body is formed with an inwardly projecting lateral flange 6. Adapted to be disposed within said body 5 is a generally 50 conventional design of sputum cup 7 that in the present instance is flanged laterally outwardly as at 8 for rest upon the inwardly directed flange 6 of the holder body 5. After the cup 7 has been disposed within 55 the body of the holder there is arranged

upon the upper open end of the cup a lid 9 of a material similar to the material of which the cup is constructed, this lid being also of rectangular configuration and resting at its edges upon the outwardly directed flange 60 8 of said cup. After this lid 9 has been applied thereto there is disposed thereon a metallic lid 10 of a shape identical with the shape of the paper lid, both of said lids being provided at their opposite ends with 65 longitudinally projecting lips 11-11 and 12-12 respectively.

The holder further consists of a slip-type lid 13 of a material similar to the material comprising the body 5 and having at its opposite ends and between the upper and lower edges thereof vertically extending outwardly projecting pockets 14-14 for receiving the lips upon the opposite ends of the plate-like lids 9 and 10. Secured to the inner side of 70 the slip lid 13 for the body 5 is a leaf spring 15 of semi-elliptical formation so that the ends thereof will engage the metallic flat-lid 10 for pressing the paper lid 9 in firm engagement with the flanged end of the sputum 75 cup 7 so as to provide an air tight joint between the upper end of the cup and said lid 9.

Riveted to the opposite side walls of the body 5 at the interior thereof and beneath 85 the upper end of the body as at 16 are the lower ends of vertically extending spring strips 17-17, the upper ends of which are bent laterally upwardly as at 18-18 which ends engage through openings in the side 90 walls of the body so as to catch above the sides of the slip lid 13 at the bottoms of the pockets 14-14 as disclosed in Figure 1 for maintaining said lid closed. Each spring strip 17 is provided intermediate its ends 95 with an outwardly projecting button 19 that is slidable through an opening in the adjacent side wall in order that the respective springs may be pressed inwardly for disengaging the upper ends thereof from the lid 100 so that the lid may be removed. Obviously, when the lid is removed, the flat lids 9 and 10 are also removed so as to permit access to the sputum cup 7 or to permit the same to be entirely removed from the body so that 105 a new cup may be disposed therein.

It will thus be seen that I have provided a highly novel, simple and efficient sputum cup holder that is well adapted for all the purposes heretofore designated and even 110

though I have herein shown and described the invention as consisting of certain detail structural elements it is nevertheless to be understood that some changes may be made 5 therein without affecting the spirit and scope of the appended claims.

Having thus described the invention, what I claim as new and desire to secure by Letters Patent is:—

- 10 1. In a sputum cup holder of the character described, an open top receptacle for receiving the cup, a lid for the receptacle, a lid for the sputum cup disposed within the receptacle lid, and complementary structure 15 between the receptacle lid and cup lid for preventing the displacement of the cup lid from said receptacle lid, said complementary construction consisting of tongues at opposed points at the edge of the cup lid and pockets at opposed points of the receptacle lid for receiving said tongues.
- 20 2. In a sputum cup holder of the class described, an open top receptacle for receiving the cup, an inwardly directed flange formed 25 on the upper edge of the receptacle and on which is adapted to rest the flanged upper edge of the cup, a lid for the cup, a removable lid for the receptacle, a plate arranged on top of the cup lid, resilient means secured to the under side of the receptacle lid engaging said plate for holding the lid for the cup in a sealing position, and means for locking the lid on the receptacle for holding the same in its pressure applying position.
- 30 3. In a sputum cup holder of the class described, an open top receptacle for receiving the cup, an inwardly directed flange formed 35 on the upper edge of the receptacle on which the flanged upper edge portion of the cup is adapted to rest, a removable lid for the receptacle, vertically extending pockets formed in the side of the lid at opposite points, a lid adapted for disposition on the flanged upper end of the cup, laterally projecting lips formed on the lid for the cup for disposition within the respective pockets of the removable lid for the receptacle, and means for applying pressure to the lid for

the cup for maintaining the same in a sealing position on the cup. 50

4. In a sputum cup holder of the class described, an open top receptacle for receiving the cup, an inwardly directed flange formed on the upper edge of the receptacle on which the flanged upper edge portion of the cup is adapted to rest, a removable lid for the receptacle, vertically extending pockets formed in the side of the lid at opposite points, a lid adapted for disposition on the flanged upper end of the cup, laterally projecting lips formed on the lid for the cup for disposition within the respective pockets of the removable lid for the receptacle, and means for applying pressure to the lid for the cup for maintaining the same in a sealing position on the cup, said means comprising a plate disposed on top of the lid for the cup, lips extending from the edge of the plate and receivable in the respective pockets of the removable lid for the receptacle, and resilient means secured to the under side of the receptacle lid and bearing against 65 said plate. 70

5. In a sputum cup holder of the class described, an open top receptacle for receiving the cup, an inwardly directed flange formed 75 on the upper edge of the receptacle on which the flanged upper edge portion of the cup is adapted to rest, a removable lid for the receptacle, vertically extending pockets formed 80 in the side of the lid at opposite points, a lid adapted for disposition on the flanged upper end of the cup, laterally projecting lips formed on the lid for the cup for disposition within the respective pockets of the removable lid for the receptacle, and means for applying pressure to the lid for the cup for maintaining the same in a sealing position on the cup, said means comprising a plate disposed on top of the lid for the cup, 85 lips extending from the edge of the plate and receivable in the respective pockets, and resilient means secured to the under side of the receptacle lid and bearing against said plate, and means for securing the lid on the 90 receptacle in a pressure applying position. 95

In testimony whereof I affix my signature.
MAC MUNDY ANDREWS.
